REAMER

Leo P. Schade, Washington, D. C.

Application June 14, 1945, Serial No. 599,439

1 Claim. (Cl. 77—72)

1

My invention relates to improvements in reamers for use in metal-working machines and reaming appliances.

The invention is designed with the primary object in view of providing a combination roughing and finishing reamer of simple form and inexpensive construction especially adapted for attaining a high-quality finish, removing most of the metal in the work prior to finishing in a manner to reduce wear on the reamer to a minimum in finishing, thereby prolonging the life of the reamer, and so as to obviate interference with finishing by metal fused on the reamer in the roughing operation.

Other and subordinate objects, also comprehended by my invention, together with the precise nature of my improvements and the manifold advantages thereof, will be readily understood when the succeeding description and claim are read with reference to the drawing accompanying and forming part of this specification.

In said drawings:

Figure 1 is a view in side elevation of a reamer embodying my improvements,

Figure 2 is a view in front end elevation, and

Figure 3 is a diagrammatic view illustrating the angle of incidence of the leading end cutting sections.

Reference being had to the drawing by numerals, my improvements have been shown therein as embodied in a "stub machine" type reamer having the usual shank 1 for insertion in a chuck, or the like, not shown, and a head 2 of the fluted type comprising longitudinal teeth 3 oblique to the axis of the head 2. For reasons presently apparent, it is essential to the practice of my invention that the head 2 be provided with an even number of teeth 3, above two, six being shown as preferable.

According to my invention, the teeth 3 are provided with leading end cutting sections the lands of which flare rearwardly, relatively, and are ground longitudinally at different angles, as regards the lands of the remaining portions of the teeth 3, in alternate teeth relative to intermediate teeth. The lands of the leading end cutting sections 4 of alternate teeth 3 are ground, as shown for illustrative purposes, at an angle of substantially 10° to the longitudinal axis A of the head 2, and the lands of the leading end cutting sections 5 of intermediate teeth 3 at a sharper angle of substantially 20°. As will be understood, the lands of the teeth 3 are ground transversely to form longitudinal cutting edges 3' on one and the same sides of all the teeth. Because of the de-

scribed angles of the lands of the leading end cutting sections 4, 5, the cutting edges 3' extend crosswise of each other in a plane, indicated by the dotted line 6, in Figure 3, which is transverse to said sections, or, in other words, the head 2. In the rear of this plane 6, said sections 5 lie outside of the orbit of operation of said sections 4, whereas, in front of the plane 6, said sections 5 lie within the orbit of operation of said sections 4.

Thus, as will be seen, in operating with the described reamer, the leading end cutting sections 4 will ream first to rough out a bore, and the leading end cutting sections 5 will follow with a finishing reaming operation, enlarging and finishing the bore. By accomplishing the roughing operations, in the manner described, wear on the leading end cutting sections 5, that is, the cutting edges 3' thereof, is reduced to a minimum, the roughing operation being performed completely in advance of finishing. Also, metal fused onto the leading end cutting sections 4, which is to say the cutting edges 3' thereof, cannot be carried to the finished bore which is cut by the leading end cutting sections 5 as a new bore after roughing is completed. As will be clear, the relative difference in the angles of incidence of the leading end cutting sections 4, 5 may be varied to suit different operating requirements, for instance, in working in different kinds of metals.

As will also be seen, by varying the angles of incidence of the leading end cutting sections 4, 5, the length of said edges, as represented by the lines R, F, may be varied to correspondingly vary the length of the cutting edges 3' of the leading end cutting sections 4 in front of the plane 6, and the length of the cutting edges 3' of the leading end cutting sections 5 in the rear of said plane, so as to predetermine the amount of metal to be cut in the roughing and finishing operations, respectively.

The foregoing will, it is believed, suffice to impart a clear understanding of my invention without further explanation.

Manifestly, the invention, as described, is susceptible of modifications without departing from the inventive concept, and right is herein reserved to such modifications as fall within the scope of the appended claim.

What I claim is:

A reamer tool comprising a cylindrical body having longitudinal alternate and intermediate cutting teeth spaced circumferentially around the same equidistantly and embodying leading end cutting sections inclined rearwardly from the

front end of the tool and outwardly of the axis of said tool, the end cutting sections of alternate teeth inclining at a lesser angle rearwardly and outwardly than the end cutting sections of the intermediate teeth to extend crosswise of the same in a plane transverse to said body whereby said end cutting sections of intermediate teeth in the rear of said plane lie outside the orbit of operation of said end cutting sections of the alternate teeth and forwardly of said plane the end cutting sections of the intermediate teeth lie within the orbit of operation of the end cutting sections of alternate teeth.
